COMBINATION PACKAGE

Frasier Smith, Wheeling, W. Va., assignor to
 Hazel-Atlas Glass Company, Wheeling, W. Va.,
 a corporation of West Virginia

Application March 10, 1937, Serial No. 130,159

5 Claims. (Cl. 206—46)

The invention relates to a novel package, and one of the objects of the invention is to provide such package by combining two glass articles, each of which is separately useful, in such manner as to form a receptacle for a powder container or other merchandise, the two glass articles being temporarily held together by a label, tape, ribbon, or the like.

More specifically, an object of the invention is to combine two glass ash trays, coasters, or the like, so that the combined trays or coasters form a receptacle to receive an article of merchandise.

Still another object of the invention is to provide a package of this nature, in which the ash trays, coasters, or the like, are provided with interlocking means to prevent relative rotation when they are in assembled relation.

A further object of the invention is to provide a glass ash tray with two sets of cigarette rests which are complementary to each other, so that all of the trays are identical and hence require only one mold, but which permit the trays when combined to interlock together to form a receptacle.

Another object of the invention is to provide a combination package of this nature, in which the label or the like uniting the two glass articles also prevents longitudinal movement of one of the glass articles with respect to the other.

A further object of the invention is to provide flat portions on the glass ash trays or coasters, so that when the trays or coasters are united to form a receptacle a label can be readily applied for the purpose of uniting the articles.

The invention will be clearly understood from the following detailed description, when taken in connection with the accompanying drawing, in which,

Figure 1 is a perspective view of two of the ash trays in disassembled relation, and a powder container illustrative of an article of merchandise which may be carried in the receptacle formed by uniting the trays; and

Figure 2 is a perspective view of the complete package; the label being broken away to more clearly illustrate the construction.

Referring to the drawing in more detail, numeral 1 indicates a glass ash tray. Two of the trays are shown in the drawing, and they are identical in construction. While I have illustrated the invention in connection with ash trays, and shall so describe the invention, yet it is to be understood that in the specification and in the claims, the term ash tray is intended to

include coasters, combination coasters and ash trays, and similar articles.

The specific ash tray illustrated is provided with two sets of cigarette rests, referred to generally by numerals 2 and 3. The ash trays are all identical in construction, so that only one mold design is necessary, but it will be noted that the cigarette rests differ. In the specific form illustrated the rest 2 of each tray has three convex surfaces 4 and two concave surfaces or depressions 5, which receive the cigarettes; while each rest 3 has two convex surfaces 6 and three concave surfaces or depressions 7, which receive the cigarettes. In other words, in the specific form illustrated one rest accommodates two cigarettes and the other rest accommodates three cigarettes, and the construction of the rests is complementary, so that when one tray is inverted upon another, with the rest 2 of one tray associated with the rest 3 of the other tray, the rests will fit together and interlock. Thus the trays not only fit together tightly to form a container, but also they are interlocked against relative rotation. It is obvious, of course, that a wide variety of different designs could be adopted to accomplish these desirable results, and the specific form disclosed herein merely illustrates one desirable form.

Before the ash trays are combined in the manner described above, an article of merchandise is placed in one of the trays. Any suitable article may be packed in the container formed by the combined ash trays, and merely as an example I have illustrated a powder box 8.

After the powder box or other article of merchandise has been placed in the container formed by inverting one ash tray upon the other, it is desirable to temporarily unite the two trays, and in uniting them it is also desirable to prevent any considerable longitudinal movement of one tray with respect to the other; it being understood that relative lateral movement and relative rotary movement are prevented by the interlocking of the cigarette rests.

It is apparent that various means could be employed to reduce or prevent relative longitudinal movement between the trays, and by longitudinal movement I mean movement longitudinally of the cigarette rests. And it is also to be understood that the invention is not limited to any particular means for preventing such movement, and that the use of any such means is not essential, for ordinarily the mere attachment of a label or the like will be entirely sufficient.

On opposite sides the trays are provided with

flat surface portions 8, and the label, tape, or ribbon 10 passes over these flat surfaces and over the bottoms of the ash trays, thereby temporarily retaining the assembled trays in container-forming position, until the combination package is ready to be opened.

In the particular form illustrated I have provided means to reduce or prevent relative longitudinal movement between the two trays. The 10 bottoms of these particular trays are provided with annular raised portions or flanges 11, and these flanges are omitted adjacent the side flat surfaces 8, thus forming shoulders 12. When a label, tape, ribbon or the like is now applied, it 15 will fit between these shoulders, and thereby prevent any considerable longitudinal movement of one tray with respect to the other.

From the foregoing description it will be apparent that I have devised a simple and attractive 20 package, in which each of the articles which are combined to form the container is separately useful; that when the articles are combined they fit tightly together and preferably interlock against relative rotary or lateral movement; that if desired the articles can also be locked against relative longitudinal movement; that the articles are readily maintained in their container-forming relation by means of a label, tape or ribbon; and that to release the merchandise in the package it 25 is only necessary to break the label, whereupon the merchandise is removed and the articles forming the container become available for use as ash trays, combination ash trays and coasters, etc.

30 Having fully described the invention, what I claim is:

1. A package consisting of two substantially identical ash trays, one inverted upon the other to form a completely closed container for merchandise, said ash trays having cigarette rests on diametrically opposed portions of the periphery thereof, the cigarette rest of each tray being complementary to each other and interfitting snugly with the cigarette rests of the other tray,

35 and band-like means encircling the two trays for holding them together.

2. A package consisting of two substantially identical ash trays, one inverted upon the other to form a completely closed container for merchandise, said ash trays having cigarette rests spaced about the periphery thereof, the cigarette rests of each tray being complementary to each other and interfitting snugly with the cigarette rests of the other tray, and means for holding the 40 two trays together in their cooperative relation.

3. A package consisting of two ash trays, one inverted upon the other to form a completely closed container for merchandise, said ash trays having cigarette rests spaced about and projecting 45 outwardly from the periphery thereof, the cigarette rests of each tray interfitting snugly with the cigarette rests of the other tray, and band-like means for holding the two trays together in their cooperative relation.

20 4. A package consisting of two ash trays, one inverted upon the other to form a completely closed container for merchandise, said ash trays having cigarette rests spaced about and projecting 50 outwardly from the periphery thereof, the cigarette rests of each tray interfitting snugly with the cigarette rests of the other tray, a label or the like for holding the two trays together in their cooperative relation, and the sides of each tray having flat portions in cooperative relation 55 to facilitate the application of the label or the like.

5. A package consisting of two ash trays, one inverted upon the other to form a completely closed container for merchandise, said ash trays having cigarette rests spaced about and projecting 60 outwardly from the periphery thereof, the cigarette rests of each tray interfitting snugly with the cigarette rests of the other tray, a label or the like for holding the two trays together in their cooperative relation, and spaced shoulders on the bottoms of the trays for limiting relative movement between the label or the like and the container formed by the combined trays.

FRASIER SMITH.
